[57] CLAIM

The ornamental design for a grapnel anchor, as shown
and described.

DESCRIPTION

FIG. 1 is an upper left perspective view of a grapnel
anchor showing my new design, the upper right per-
spective view being a mirror image of that shown; and
FIG. 2 is a lower right perspective thereof, the lower
left perspective view being a mirror image of that
shown.

FIG. 1

FIG. 2
